UNITED STATES PATENT OFFICE

166,252

ERASER

Faust Achilles Fusco, Kew Gardens Hills, N. Y., assignor to Eagle Pencil Company, a corporation of Delaware

Application May 11, 1951, Serial No. 15,138

Term of patent 14 years

(Cl. D74—7)

To all whom it may concern:

Be it known that I, Faust Achilles Fusco, a citizen of the United States and residing at Kew Gardens Hills, Long Island, county of Queens, and State of New York, have invented a new, original, and ornamental Design for an Eraser, of which the following is a specification, reference being had to the accompanying drawings, forming part thereof, and in which

Fig. 1 is a side elevational view of an eraser, showing my new design,

Fig. 2 is an edge elevational view thereof,

Fig. 3 is a sectional view taken along the line 3—3 of Fig. 1.

I claim:

The ornamental design for an eraser, substantially as shown.

FAUST ACHILLES FUSCO.
